CLAIM

The ornamental design for a combined clock and picture frame, as shown and described.

DESCRIPTION

FIG. 1 is a top front perspective view of a combined clock and picture frame showing my new design;
FIG. 2 is a top rear perspective view of FIG. 1;
FIG. 3 is a top plan view thereof in a closed position, the bottom being a mirror image;
FIG. 4 is a left side elevational view of FIG. 3; and,
FIG. 5 is a right side elevational view of FIG. 3.
